CLAIM

The ornamental design for a packaging for jigsaw puzzle, as shown and described.

DESCRIPTION

FIG. 1 is a top, front and left-side perspective view of packaging for jigsaw puzzle embodying my design;

FIG. 2 is a right-side elevational view thereof;

FIG. 3 is a left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the jigsaw puzzle pieces is for illustrative purposes only, and forms no part of the claimed design.
